Primary Examiner — Ian Simmons*Assistant Examiner* — Dana L Meyrow(74) *Attorney, Agent, or Firm* — Marshall, Gerstein & Borun LLP(57) **CLAIM**

The ornamental design for a jar, as shown and described.

DESCRIPTION

FIG. 1 is a top perspective view of a jar showing our new design, with the broken lines immediately adjacent to the shaded areas in the views represent the boundaries of the claimed design;

FIG. 2 is a front view of the jar of FIG. 1;

FIG. 3 is a top plan view of the jar of FIG. 1;

FIG. 4 is a bottom plan view of the jar of FIG. 1;

FIG. 5 is a perspective view showing the jar of FIG. 1, without the lid;

FIG. 6 is a front view of the jar of FIG. 5;

FIG. 7 is a top plan view of the jar of FIG. 5; and,

FIG. 8 is a bottom plan view of the jar of FIG. 5.

As illustrated, the jar portion of the claim is transparent and the lid portion is opaque. The stippling on the top surface of the lid illustrates contrasting surface texture.

The jar is shown broken in the middle to indicate no particular height is being claimed, with the understanding that the portion of the article not shown forms no part of the claimed design as patentability is based only on those portions of the article that are shown in solid lines.
